ABSTRACT OF THE DISCLOSURE

An electric sign device for displaying an image on a screen formed by a number of electric luminous elements mounted in stages. An original picture on a tape is read by photoelectric conversion type readers. The output of the readers is fed to shift registers to selectively control the energization of the luminous elements to form bright and dark areas corresponding to the original picture. The shift pulses are obtained by using a number of dots provided on the tape in its lengthwise direction.

This invention relates to an improvement in electric sign devices of the type provided with a sign board having a substantially rectangular screen formed of a multiplicity of electric luminous elements and a signal generator for movingly reproducing on the screen an image having lighted areas and darkened areas corresponding to an original picture provided on a tape.

The first object of the present invention is to provide an electric sign device of the type described in which the structure of the generator for producing electric signals corresponding to an original picture on a moving tape is extremely simplified.

The second object of the present invention is to provide an electric sign device of the type described in which the number of wires connecting the generator with the sign board is greatly reduced. That is, the invention intends to minimize the amount of wires required when the sign board is disposed at a place remote from the signal generator.

The third object of the present invention is to provide an electric sign device in which the use of a bulky mercury switch mechanism in the generator as has been the case with prior devices is completely eliminated and in which even if such mercury switch mechanism should be used the generation of detrimental mercury vapor can be minimized.

The fourth object of the present invention is to provide an electric sign device of the type described in which arrangement is made so as to facilitate positive-negative inversion of an image produced on the sign board or to facilitate impartation of color thereto.

According to the present invention, there is provided an electric sign device comprising a sign board having a substantially rectangular screen formed of a multiplicity of electric luminous elements arranged in multiple stages, an electric signal generator for generating electric signals for movingly reproducing on said screen an image corresponding to an original picture provided on a tape, means for supplying to said generator input signals representing a linear state of a certain position on said tape, means for applying output signals from said generator to a predetermined number of the elements linearly disposed in one stage of the multiplicity of electric luminous elements arranged in multiple stages and electronic circuits for controlling electric signals to be supplied to the electric luminous elements in the stages other than

2

said stage, each of said electronic circuits being disposed between one electric luminous element in each stage and one electric luminous element in the preceding stage.

The above and other objects, advantages and features of the present invention will become apparent from the following description with reference to the accompanying drawings, in which:

FIG. 1 is a perspective view of a signal generator employed in the electric sign device embodying the present invention;

FIG. 2 is a schematic diagram of parts of a circuit network employed in one embodiment of the electric sign device of the present invention;

FIG. 3 is a schematic diagram of parts of a circuit network employed in another embodiment according to the present invention;

FIG. 4 is a schematic illustration of waveforms at various points in the circuit network shown in FIG. 3;

FIG. 5 is a plan view of part of a tape which can conveniently be used with the electric sign device of the present invention; and

FIG. 6 is a schematic diagram of a circuit network of the present invention for imparting color to images appearing on the sign board.

An important feature of the device according to the present invention resides in that electric signals corresponding to an original picture are not derived from a planar state at each instantaneous position of a tape moving over a signal generator but from a linear state obtained by finely dividing such planar state. In the present invention, these electric signals are utilized to directly effect on-off control of only a predetermined portion of entire electric luminous elements, and on-off control of each element of the remaining greater portion of the electric luminous elements is effected in a manner that an electric signal controlled by an electronic circuit provided between each electric luminous element and a preceding electric luminous element positioned at the pre-stage is utilized to make on-off control of each element.

Some of preferred embodiments of this invention will now be described in detail hereunder.

In FIG. 1 showing in perspective fashion an example of the signal generator employed in the invention, $r_1, r_2, r_3 \dots r_n$ designate photoconductive cells formed of CdS, CdSe or like material. On the upper face of a base B of electrically insulating material these photoconductive cells are disposed in a straight line, with an even space between adjacent cells. A transparent tape T moves in a direction as for example shown by an arrow through a gap between the base B and a light source L disposed thereabove by being aided by a suitable feed mechanism. An original picture C is drawn on the tape surface with an opaque paint material.

The photoconductive cells $r_1, r_2, r_3, \dots r_n$ maintain small resistance by the light emitted from the light source L unless the original picture C appears in the gap between the photoconductive cells $r_1, r_2, r_3, \dots r_n$ and the light source L. When however a linear strip portion of the original picture C intrudes into the gap with the advancing movement of the moving tape T, the path of the light towards the photo-conductive cells is interrupted and the resistance of the second photoconductive cell r_2 makes an abrupt increase in the case illustrated in FIG. 1.

As will be apparent from FIG. 2 showing parts of a circuit network employed in one embodiment of the device of the present invention, the increase in the resistance of the photoconductive cell r_2 results in reduction of voltage across a resistor R_1 since the photoconductive cell r_2 is connected to a source of direct current supply $+B$ through the resistor R_1 . Therefore this causes generation of one pulse signal in the output of a waveform shaping circuit F. This pulse signal is applied to one of units T_{21} ,

such as a transistor, forming together with other unit T_{21}' a bi-stable multi-vibrator which acts as a pre-circuit for an electric luminous element l_{21} positioned in line 2, stage 1 of the sign board. Thus, the unit T_{21} is driven to its "cut off" state while the other unit T_{21}' which may also be a transistor is driven to its "on" state. As a result, current conducts through a relay coil Re_{21} to change over switches S_{21} and S_{21}' to respective operative positions. Consequently, the electric luminous element l_{21} positioned in line 2, stage 1 of the sign board is lit.

In this manner, the optical state (that is transparent or not) of the portion of picture superimposed at a certain instant on the photoconductive cells $r_1, r_2, r_3, \dots, r_n$ causes electrical change in photoconductive cells corresponding to above-mentioned portion of picture, and electrical signals are obtained therefrom.

These signals effect direct on-off control of the elements disposed in the first stage of the multiplicity of electric luminous elements arranged in multiple stages to form the screen of the sign board.

In the embodiment shown in FIG. 1, a moving tape T of light transparent nature and an original picture C of opaque nature have been employed to obtain electric signals from the light transmitted through the tape T. However, a moving tape T of high reflexivity and an original picture C of low reflexivity may be used so that electric signals corresponding to the original picture may be derived from reflected light.

According to the invention, an arrangement is provided so that, in the course of the above manner of control of luminous elements disposed in the first stage of the multiplicity of electric luminous elements, positive pulses are periodically supplied at predetermined time intervals to a terminal p which is connected with the output of a suitable pulse generator. One positive pulse supplied to the terminal p is transmitted through a diode d_{21} and the switch S_{21}' to one of units T_{22} , such as a transistor, forming together with other unit T_{22} , a bi-stable multi-vibrator which acts as a pre-circuit for an electric luminous element l_{22} disposed in line 2, stage 2 of the sign board. Therefore the unit T_{22} is driven to its "cut off" state while the other unit T_{22}' which may also be a transistor is driven to its "on" state, and finally the electric luminous element l_{22} is energized. When a succeeding positive pulse is supplied to the terminal p, an electric luminous element l_{23} disposed in line 2, stage 3 is energized this time. Thus, the electric luminous elements disposed in line 2 of the sign board are successively subjected to sequence control in the direction of line 2 and the time interval of sequence control is in synchronism with the time intervals of generation of the pulses applied to the terminal p.

It will be understood that, while this on-off control in the direction of the line proceeds, new electric signals corresponding to the advancing original picture are successively generated by the photoconductive cell r_2 and these signals directly (for the first stage) and indirectly (for the stages after and including the second stage) effect the on-off control of electric luminous elements $l_{21}, l_{22}, l_{23}, \dots$ one after another. Further it is possible to effect positive-negative inversion of the bright-dark contrast image by connecting the unit T_{21}' with the output of the waveform shaping circuit F instead of the previous connection between the unit T_{21} and the output of the circuit F. It is to be understood that any one of the photoconductive cells $r_1, r_2, \dots, r_n$ is provided with a circuit as shown in FIG. 2 since the circuit network shown in FIG. 2 does not represent the entirety of the device of the present invention and merely represents that portion which is associated with the specific photoconductive cell r_2 .

The circuit network employed in the device according to the present invention may be modified, for example, as shown in FIG. 3. A modified example of the circuit net-

work shown in FIG. 3 will next be described with further reference to FIGS. 1, 4 and 5.

In the circuit network of FIG. 3, the photoconductive cell r_2 is connected through a resistor R_{101} to a source of direct current supply and a differentiating circuit comprising a condenser C_{101} and a resistor R_{102} is added for cooperation with the photoconductive cell r_2 . Suppose now a moment at which the tape T is advanced further with the result that an original picture having existed in the gap between the photoconductive cell r_2 and the light source L is shifted so that a transparent portion of the tape now exists in the gap and a positive pulse as shown by p_1 in p of FIG. 4 is applied to a terminal p. At this moment, the resistance of the photoconductive cell r_2 makes an abrupt decrease and a positive signal as shown by a_1 in a of FIG. 4 is generated at point a in FIG. 3. Since this signal drives a transistor Tr_1 to its "cut off" state and a transistor Tr_2 to its "on" state, condensers C_{102} and C_{103} start discharging and charging, respectively, and potential at point b in FIG. 3 decreases gradually as shown by b_1 in b of FIG. 4 until finally it equals the potential $-B$. Under this situation, current flowing through a relay coil Re_{121} is cut to urge a switch S_{121} to its open position so that an electric luminous element l_{121} disposed in line 2, stage 1 of the sign board is deenergized. On the other hand, the pulse p_1 applied to the terminal p is supplied through a resistor R_{103} and a diode d_{101} to the base electrode of a transistor Tr_4 which, in conjunction with another transistor Tr_3 , forms a bi-stable multivibrator which acts as a pre-circuit for an electric luminous element l_{122} disposed in line 2, stage 2 of the sign board. At the moment when the pulse p_1 is applied to the terminal p the potential at point b is immediately before its gradual decrease and is still high. Therefore the pulse p_1 can not flow into the system through a diode d_{102} . Although the pulse p_1 applied to the terminal p is also transmitted to point c through a resistor R_{104} and a diode d_{103} , the transistor Tr_1 is not affected at all because the transistor Tr_1 is being driven to its "cut off" state.

The combination of these two actions drives the transistors Tr_3 and Tr_4 to their "on" state and "cut off" state, respectively, and as a result, the pulse p_1 applied to the terminal p causes the electric luminous element l_{121} to be deenergized, while the electric luminous element l_{122} disposed in line 2, stage 2 of the sign board is urged to its energized state as if it follows the past behaviour of the element l_{121} .

Suppose then a moment at which a second pulse as shown by p_2 in p of FIG. 4 is applied to the terminal p in FIG. 3. Also assume that a transparent portion of the tape T again exists in the gap between the photoconductive cell r_2 and the light source L at this moment. In this case no electric signal appears at point a and therefore the element l_{121} continues its deenergized state. Since, on the other hand, the potential at point b is now sufficiently low, the pulse p_2 applied to the terminal p is conducted into the system through the resistor R_{103} and the diode d_{102} but not through the diode d_{101} . Further, since the potential at point C is now high, the pulse p_2 is not conducted through the diode d_{103} but is conducted to the base electrode of the transistor Tr_3 through the resistor R_{104} and a diode d_{104} . Thus, the transistors Tr_3 and Tr_4 are driven to their "cut off" state and "on" state, respectively, and finally the element l_{122} is urged to its deenergized state as if it follows the way the element l_{121} behaved in past.

When, however, an original picture C of opaque nature is inserted in the above gap at the moment when the pulse as shown by p_2 in p of FIG. 4 is applied to the terminal p, the resistance of the photoconductive cell r_2 increases with the result that a negative signal as shown by a_2 in FIG. 4 is generated at point a in FIG. 3. This causes inversion of the states of the transistors Tr_1 and Tr_2 , that is, the transistors Tr_1 and Tr_2 are now driven to their "on" state and "cut off" state, respectively. As a result, the po-

tential at point *b* makes a gradual increase as shown by b_2 in *b* of FIG. 4 and current conducting through the relay coil Re_{121} urges the switch S_{121} to its closed position so that the element l_{121} is finally energized. The transistor Tr_2 in its "cut off" state assists discharging of the condenser C_{103} and the potential at point *c* makes a gradual decrease as shown by c_2 in *c* of FIG. 4. On the other hand, the pulse p_2 applied to the terminal *p* is conducted to point *b* which is at a potential immediately before making a gradual increase and is not conducted to the diode d_{101} . Since however the potential at point *c* is still high as it is immediately before making its gradual decrease, the pulse p_2 is applied through the resistor R_{104} and the diode d_{104} to the base electrode of the transistor Tr_3 to drive the transistor Tr_3 to its "cut off" state to thereby urge the switch S_{122} to its open position. Consequently the element l_{122} is urged to its deenergized state as if it follows the way the element l_{121} behaved in the past.

An important matter in connection with the present circuit arrangement is that the original picture *C* depicted on the moving tape *T* must be strictly synchronized with the time intervals of generation of pulses applied to the terminal *p* because a bright-dark contrast image appearing on the sign board is generated in accordance with the time intervals of generation of pulses applied to the terminal *p* from a certain external means not shown in the figure and is successively fed in the direction of the line. A concrete example will be described as follows in order to explain the above matter in more detail. Assume now that an original picture, for example, a sign "11" is passed through the gap between the light source *L* and the photoconductive cells $r_1, r_2, r_3, \dots, r_n$ in FIG. 1. In this case, satisfactory sign display operation can be effected when a first pulse is applied to the terminal *p* as soon as the photoconductive cells $r_1, r_2, r_3, \dots, r_n$ catch the right-hand half or "1" of the original picture and a second pulse is applied to the terminal *p* as soon as the photoconductive cells catch the left-hand half or "1" of the original picture. However, a bright-dark contrast image corresponding to the original picture can not be displayed on the sign board if a first pulse is applied to the terminal *p* immediately before the original picture "11" reaches the photoconductive cells, a second pulse is applied at the intermediate position of the picture on the cells, and a third pulse is applied immediately after the picture has passed over the cells.

In order to overcome such difficulty, the present invention proposes a new type of moving tape *T'* which is provided with a multiplicity of black dots *E* printed on its lower edge in equally spaced relation as shown in a plan view of FIG. 5. It will be understood that the above difficulty can be overcome by depicting an original picture *C'* in a manner to correspond with the group of black dots *E* and by using the group of black dots *E* to generate pulses for application to the terminal *p*.

From the above description exemplifying the preferred embodiments, it will be understood that, in the device according to the present invention, electric signals derived from an original picture are solely supplied to electric luminous elements disposed in the first stage of a multiplicity of electric luminous elements arranged in multiple stages to form the screen of the sign board, and therefore connecting between the remaining electric luminous elements occupying the greater portion of the element group and a signal generator including photoconductive cells, light source, moving tape, etc. are utterly unnecessary. This is especially advantageous when the sign board and the signal generator are disposed remote from each other because an amount of connecting wires required for connection therebetween can greatly be reduced. Further, the electric luminous elements connected with the signal generator may not necessary form the screen of the sign

board, and the photoconductive cells employed herein may be replaced by other types of elements such as photoelectric converting elements.

An example of an additional circuit for imparting color to a bright-dark contrast image to be displayed on the sign board will next be described with reference to FIG. 6. In FIG. 6, each of a multiplicity of electric luminous elements $l_{221}, l_{222}, l_{223}, \dots$ forming the screen of the sign board comprises a set of lamps emitting colors different from one another, for example, a lamp l_R for emitting red light, a lamp l_B for emitting blue light and a lamp l_G for emitting green light. Assume now that both of photoconductive cells r_x and r_y are held in their non-conducting state with or without relation to the advancing movement of a tape. Then relay switches S_x and S_y are held at relative positions as shown and as relay switches $S_{221}, S_{222}, S_{223}, \dots$ are successively closed a bright-dark contrast image displayed on the sign board will be colored in red. In case the photoconductive cell r_x is held in its nonconducting state and the photoconductive cell r_y is held in its conducting state with the result that the switch S_y is urged to the other operative position, the bright-dark contrast image will now be colored in blue. The image will be colored in green when both of the cells r_x and r_y are held at their conducting state.

What is claimed is:

1. An electric sign device comprising a sign board having a screen formed by a plurality of electric luminous elements arranged in multiple stages, tape means having an original picture provided thereon, a plurality of sequentially arranged, optically detectable dots provided along one edge of said tape, means to drive said tape, photo-electric conversion type reader means mounted to read said tape and form output signals representing an optical scan of a linear strip portion of the picture on the tape and shift pulses corresponding to scanning of said dots, a plurality of shift registers operatively connected to receive said output signals and shift pulses and to correspondingly control energization of said luminous elements, each said shift register being disposed between one electric luminous element in one stage and an electric luminous element in the preceding stage, whereby bright and dark images corresponding to the original picture are formed on the screen.
2. An electric sign device according to claim 1, wherein said shift registers comprise bi-stable multivibrators in cascade connection.
3. An electric sign device according to claim 1, wherein said reader means comprise a plurality of photo-electric converting elements arranged in a row in suitably spaced relationship and at least one light source, said tape being passed between said converting elements and said light source.
4. An electric sign device according to claim 1, wherein said electric luminous elements each comprise a plurality of lamps of different colors.
